GAS CLEANER

Owen R. Rice, Chicago, Ill., assignor to Freyn
Engineering Company, Chicago, Ill., a corpora-
tion of Maine

Application June 22, 1936, Serial No. 86,603

4 Claims. (Cl. 183—34)

The present invention relates to improvements in gas cleaning means.

More particularly the present invention relates to means for the removal of dust or the like from gas such as delivered by blast furnaces. Gas cleaning devices are in service and are giving good account of themselves which rely upon the effect of centrifugal force in removing the relatively heavy dust particles from the gas. Certain installations of the kind referred to involve structure having curvilinear passageways for the gas. The gas is wetted and, as a result, the walls defining said curvilinear passageways are wetted and serve to collect dust particles which strike thereagainst during the passage of the gas through said passageways.

An object of the present invention is to provide gas cleaning means based fundamentally upon the principles of the installations above discussed in which maintenance problems are reduced to a minimum.

A further object is to provide gas cleaning means which is simple in construction and operation and which may be repaired without putting said gas cleaning means completely out of operation.

A further object is to provide gas cleaning means operating upon the principle of centrifugal force which is well adapted to meet the needs of commercial operation.

Further objects will appear as the description proceeds.

Referring to the drawings—

Figure 1 is a top plan view of one embodiment of the present invention;

Figure 2 is a view in end elevation of the construction shown in Figure 1;

Figures 3 and 4 are plan and end elevational views, respectively, showing a modification of the structure shown in Figures 1 and 2;

Figure 5 is a view in side elevation of the structure shown in Figure 3;

Figure 6 is a sectional view, the top being removed, of a portion of the structure shown in Figure 3;

Figure 7 is a sectional view taken along the plane indicated by the arrows 7—7 of Figure 6;

Figure 8 is a view showing how an assemblage of vanes may be lowered into a structure for receiving said assemblage of vanes; and

Figure 9 is a view on an enlarged scale of a detail of construction.

Referring first to Figures 1 and 2, these figures show a construction in which dirty gas is conducted through the main 10 to an elbow 11. Disposed in position to spray water into the dirty gas from the main 10 is the spraying device 12. The dirty gas charged with water from the spraying device 12 is carried through the down pipe 13 to the pipe 14. Said pipe 14 has aligned there-

with the gas main 15, and communication between the pipe 14 and the gas main 15 is controlled by the valve 16. Symmetrically disposed with respect to the axis of the gas main 16 are the two curvilinear conduits 17 and 18, each of which is U-shaped in general contour and each of which provides a by-pass around the valve 16 from the pipe 13 to the gas main 15. Each of the conduits 17 and 18 is provided with the pair of valves 19—19 located adjacent to the extremities of the corresponding conduit 17 or 18. Said valves 16 and 19—19 have the function of controlling the passage of gas through the gas main 15, the curvilinear conduit 17 and/or the curvilinear conduit 18.

The down pipe 13 may extend below the level of the gas main 15 and the curvilinear conduits 17 and 18 to provide a receptacle 20 for dirty water which may be drawn off through the trap 21, said trap serving to prevent the escape of gas therethrough.

The construction shown in Figures 3, 4 and 5 will be clear without detailed explanation. In said figures the dirty gas pipe 10a is disposed in alignment with the gas main 15, and communication therebetween is controlled by the valve 16. Communication between the dirty gas pipe 10a and the gas main 15 around the valve 16 is provided by the two curvilinear conduits 17a and 18a, each of which is controlled by a pair of valves 19a—19a disposed adjacent to the extremities thereof. A spraying device 12a is provided for spraying water into the dirty gas within the dirty gas pipe 10a. Said dirty gas pipe 10a may be provided with the drain 22 for drawing off dirty water. Said pipe 10a may be provided with the wash-out plug 23, whereby a stream of water may be directed into the dirty gas pipe 10a to wash out accumulations of mud which may collect therein.

Figures 6, 7, 8 and 9 illustrate a preferred vane assembly which may be used in connection with the curvilinear conduit 17a or the curvilinear conduit 18a. As the description proceeds it will be clear that the construction shown in Figures 6 to 9 inclusive may be used in the curvilinear conduits 17 and 18 of Figures 1 and 2.

The particular curvilinear conduit chosen for illustration in Figures 6 to 9 is the conduit 18a of Figures 3, 4 and 5. This conduit includes a casing 24 comprising half of an annulus, the cross-sectional contour of said casing 24 being U-shaped. Disposed at the upper extremities of the inner and outer walls of the casing 24 are angles 25—25 for the reception of a cover 26, which may be bolted to said flanges 25—25 to provide a gas-tight receptacle.

Disposed within the casing 24 are a pair of vane assemblies indicated in Figure 8 by the numeral 26. Each of said assemblies 26 com-

prises a plurality of vanes 27-27 curved about the axis of the annular conduit 18a. Each of said vanes 27-27 has a curvilinear extent of approximately 90 degrees. Said vanes are held in rigid spaced relationship with one another by means of the support bridges 28-28 at the bottoms of said vanes 27-27 and by the bridges 29-29 located at the tops of said vanes. The upper edges of the vanes 27-27 are provided with angles 30-30 adapted to be secured to the bridges 29-29. Said bridges 29-29 have extending end portions adapted to rest upon and to be pinned to clips 31-31 secured to the opposite side walls of the U-shaped casing 24. As shown, the lower extremities of the vanes 27-27 are provided with lugs 32-32 having threaded extremities adapted to be secured to the supporting bridges 28-28. The supporting bridges 28-28 have downwardly extending feet 33-33 which are useful in assembling the vanes before mounting in the casing. Disposed adjacent to the bottom of the casing 24 are a plurality of spray nozzles 34-34 for directing streams of water along said bottom wall. Preferably, said streams of water should be directed oppositely to the gas flow. Water from the nozzles 34-34 will wash deposit which has collected in the bottom of the casing 24 toward the drain 22.

The surfaces of the vanes 27-27 and the inside surfaces of the walls of the curvilinear conduits 17, 18, 17a and 18a will preferably be covered with rubber or its equivalent. Rubber or the like has the very advantageous quality of causing water to spread readily thereupon, presenting a surface very well adapted to catch dust particles in the gas impinging upon such surfaces.

The mode of operation of the constructions above described will be clear without detailed explanation. The assemblies 26 may be readily inserted in place in their curvilinear conduits, or may be readily removed for repairs or replacement.

Under normal operation water will be sprayed into the dirty gas entering the device from the pipe 10 (Figs. 1 and 2) or the pipe 10a (Figs. 3, 4 and 5). Under such normal operation the valve 16 will be in closed position and the valves 19-19 (Figs. 1 and 2) or the valves 19a-19a (Figs. 3, 4 and 5) will be open. Under these conditions the wetted dirty gas will be directed through the curvilinear conduits 17-18 (Figs. 1 and 2) or 17a-18a (Figs. 3, 4 and 5). The curvilinear vanes 27-27, together with the curvilinear inside surfaces of the conduits 17-18 or 17a-18a, will cause the gases to take up a curvilinear course of movement from the incoming dirty gas pipe to the gas main 15. The dust particles, being relatively heavy, will tend to travel in straight lines, whereby they will impinge upon the water-coated rubber surfaces of said conduits or vanes. There will also be a continual deposition of water particles upon said rubber-coated surfaces, whereby said surfaces will be continually wetted. The dirt collected from the gas will flow down the vertical surfaces to the bottoms of the curvilinear conduits 17-18 (Figs. 1 and 2) or the curvilinear conduits 17a-18a (Figs. 3, 4 and 5) and will tend to collect along the bottom walls of said curvilinear conduits. Said dirt will be flushed out by the water from the spray nozzles 34-34 and will be discharged through the trap 21 (Figs. 1 and 2) or the drain 22 (Figs. 3, 4 and 5).

Though certain preferred embodiments of the present invention have been described in detail, many modifications will occur to those skilled in the art. It is intended to cover all such modifications that fall within the scope of the appended 5 claims.

What is claimed is—

1. In gas cleaning means, in combination, a curved conduit and an assembly of vanes within said conduit, said vanes being spaced 10 apart and disposed vertically and conforming to the curvature of said conduit, bridging means for holding said vanes in assembled relationship with each other, supporting means on the interior of said conduit cooperating with certain 15 of said bridging means to suspend said assembly of vanes in spaced relationship with the bottom of said conduit, and a plurality of flushing means spaced circumferentially of said conduit adjacent to the bottom thereof for squirting water 20 along said bottom.

2. In gas cleaning means, in combination, a curved conduit and a plurality of assemblies of vertically disposed vanes within said conduit, the vanes of one of said assemblies being disposed 25 relative to the vanes of the others of said assemblies for providing smooth curved passageways through said assemblies, each of said assemblies being provided with bridging means for holding the vanes thereof in assembled relationship with each other, supporting means on the interior of said conduit co-operating with certain 30 of said bridging means, said supporting means being disposed in position to hold said assemblies above the bottom of said conduit, and a plurality of flushing means disposed circumferentially of said conduit adjacent to the bottom thereof for squirting water along said bottom.

3. In gas cleaning means, in combination, a curved conduit which is substantially U-shaped 40 in horizontal cross section, a removable cover plate for said conduit, an assembly of vertically disposed vanes within said conduit, said vanes being spaced apart and conforming to the curvature of said conduit to provide a plurality of 45 passageways through said conduit, bridging means for holding said vanes in assembled relationship with each other, supporting means for said bridging means readily accessible at the top of said conduit, and a plurality of flushing means disposed circumferentially of said conduit adjacent to the bottom thereof for squirting water along said bottom.

4. In gas cleaning means, in combination, a curved conduit and an assembly of vanes within 55 said conduit, said vanes being spaced apart and disposed vertically and conforming to the curvature of said conduit, said vanes being provided at their tops individually with angle members extending circumferentially for substantially the 60 entire length of said vanes, said angle members serving to preserve the radius of curvature of their respective vanes and also constituting means for suspending said vanes from above, bridging means secured to said angle members 65 for holding said vanes in assembled relationship with each other, supporting means on the interior of said conduit cooperating with certain of said bridging means to suspend said assembly of vanes in spaced relationship with the bottom 70 of said conduit, and means for directing flushing water along the bottom of said conduit.
